UNITED STATES PATENT OFFICE.

ARTHUR HISTON, OF YONKERS, ASSIGNOR OF ONE-HALF TO OTIS BROTHERS & COMPANY, OF NEW YORK, N. Y.

GAS-ENGINE.

SPECIFICATION forming part of Letters Patent No. 400,458, dated April 2, 1889.

Application filed April 20, 1888. Serial No. 271,283. (No model.) Patented in England October 15, 1887, No. 13,991.

To all whom it may concern:

Be it known that I, ARTHUR HISTON, a subject of the Queen of Great Britain, residing at Yonkers, county of Westchester, State of New York, have invented certain new and useful Improvements in Gas-Engines, (for which I have obtained Letters Patent in England, dated October 15, 1887, No. 13,991,) of which the following is a full, clear, and exact specification.

My invention relates to that class of gas-engines in which a reciprocating piston is propelled in one direction in a cylinder by the explosion of a gaseous mixture within the cylinder; and my invention consists of certain means, fully set forth hereinafter, of controlling the inlet and discharge of the gases.

In the drawings, Figure 1 is a sectional elevation of a gas-engine embodying my improvement. Fig. 2 is a part sectional plan. Fig. 3 is a section on the line 3 3, Fig. 2, looking in the direction of the arrow. Fig. 4 is a section on the line 4 4, Fig. 3, the piston being omitted.

The bed A of the engine supports a horizontal cylinder, B, surrounded by the usual water-jacket, open at the forward end, and containing a pump-piston, C, to which is jointed a rod, D, connecting the piston with the crank of a crank-shaft, E, supported in pillow-boxes on the bed and carrying a fly-wheel, F. The cylinder B is enlarged beyond the point reached by the piston on its rear motion to form an explosion-chamber, x, with which communicates a port, 2, for the admission of air, which port is closed by a check-valve, 3, opening upwardly, so that the air will be drawn into the cylinder on the forward motion of the piston, the valve 3 closing

as the piston moves back. With the combustion-chamber x at one side and above the port 2 communicates a port, 4, leading to a valve-casing, 5, with which communicates a gas-pipe, 7, and a valve, 6, closing the passage through the valve-casing 5, is secured to a stem, 8, provided with a head, 9, between which and the casing intervenes a coiled spring, 10, that tends to maintain the valve 6 upon its seat. In bearings upon the cylinder, in line with the valve-stem 8, is supported a sliding rod, 12, to which is jointed a con-

necting-rod, 13, extending to the strap 14 of an eccentric, 15, upon the crank-shaft E, whereby the rod 12 is reciprocated and carried to and from the stem 8 to lift the valve 6 and permit it to close under the action of the spring, thereby regulating the flow of gas to the cylinder. The exhaust-port y communicates with the cylinder B in position to be uncovered by the piston after the latter passes forward beyond the middle of its stroke, and the said port y communicates with a casing, 16, and with the exhaust-pipe 17, through a passage controlled by a valve, 18, the stem 19 of which is connected with the lever 20, jointed at its opposite ends to a connection upon the rod 13, and pivoted between its ends to a bracket supported by the cylinder, so that as the rod 13 is moved backward it will open the exhaust-valve as the piston uncovers the port y, and will then open the gas-inlet valve to admit a new charge. A spring, 21, bearing upon the head of the exhaust-valve spindle, tends to maintain the exhaust-valve in its seat, and the parts are preferably so arranged that the gas-valve may be opened slightly ahead of the opening of the exhaust-valve, which latter will be opened just prior to the time when the piston on its forward movement passes the exhaust-port y.

In connection with a suitable ignitor, the operations of the above-described parts will be as follows: When the piston C begins its forward stroke, the valve 3 is lifted and the air passes freely into the cylinder behind the piston, and a portion of gas is also admitted through the gas-port, and the mixture is compressed upon the backward movement of the piston, and is exploded just as the piston reaches the limit of its backward movement. Upon the next forward movement of the piston the valve 3 occupies its seat until the piston passes the exhaust-port, when the pressure within the cylinder will be relieved, a portion of the spent gases passing out of the exhaust, another portion following the piston and remaining in the cylinder, while the valve 3 rises and permits the inflow of the volume of fresh air, and a volume of gas passes into the cylinder through the port 4 and mixes with the air. As the piston commences its return-stroke, the exhaust-valve and gas-valve

are closed and the air-valve 3 takes its seat automatically, and the gaseous mixture is compressed within the explosion-chamber and there explodes as the piston reaches the limit of its rear movement, the operations being then repeated and maintaining a continuous rotation of the shaft and fly-wheel.

It will be seen that by the arrangement of parts described I operate both the gas-valve and the exhaust-valve from a single eccentric, and that by a slight adjustment of the position of the contacting parts I can vary the time of the opening of the valves as may be desired.

Without limiting myself to the precise construction and arrangement of parts described, I claim—

1. A cylinder provided at the rear end with separate ports communicating one with the external air and the other with a gas-supply pipe, an exhaust-port arranged to be uncovered on the forward movement of the piston, valves controlling the gas-passage, the air-port, and the exhaust-passage, and connections between the gas and exhaust valves, and an eccentric-rod operated by an eccentric upon the crank-shaft of the engine, substantially as set forth.

2. The combination, in a gas-engine, of a cylinder and reciprocating piston, an air-inlet in the cylinder provided with a valve, a separate gas-inlet in the cylinder, also provided with a valve, an exhaust provided with a valve, and a reciprocating rod supported in bearings outside of the cylinder, and separate connections between the said rod and both the gas and exhaust valves, substantially as set forth.

3. The combination, with the gas and exhaust valves of a gas-engine, of valve-stems extending through the valve-chests, springs bearing upon said stems to hold the said valves on their seats, a reciprocating rod arranged to contact with the independent stem of the gas-valve, and a lever connecting said rod with the stem of the exhaust-valve, substantially as set forth.

In testimony whereof I have signed my name to this specification in the presence of two subscribing witnesses.

ARTHUR HISTON.
